[57] **CLAIM**

The ornamental design for a front panel for electronic equipment, as shown and described.

DESCRIPTION

FIG. 1 is a front, top, and right side perspective view of a front panel showing our new design;

FIG. 2 is a bottom plan view thereof;

FIG. 3 is a rear elevation view thereof; and

FIG. 4 is a left side elevation view; and,

FIG. 5 is a perspective view thereof, shown without broken lines. The broken line showing is for illustrative purposes only, and forms no part of the claimed design.
